UNITED STATES PATENT OFFICE.

FRANK W. TIESING, OF NEW HAVEN, CONN., ASSIGNOR TO THE SCHOLL-HORN & TIESING MANUFACTURING COMPANY, OF SAME PLACE.

COACH-HINGE.

SPECIFICATION forming part of Letters Patent No. 239,201, dated March 22, 1881.

Application filed January 31, 1881. (Model.)

To all whom it may concern:

Be it known that I, FRANK W. TIESING, of New Haven, in the county of New Haven and State of Connecticut, have invented a new Improvement in Concealed Hinges; and I do hereby declare the following, when taken in connection with the accompanying drawings and the letters of reference marked thereon, to be a full, clear, and exact description of the same, and which said drawings constitute part of this specification, and represent, in—

Figure 1, a front view as in the open condition; Fig. 2, an end or top view with the parts in their closed condition; Fig. 3, a vertical section on line X X; Fig. 4, a perspective view of the shoe.

This invention relates to an improvement in that class of hinges which are used for hanging coach or carriage doors, and commonly called "concealed hinges," from the fact that when the door is closed the hinge is entirely hidden. These hinges consist of a plate attached to the door-post, a second plate attached to the door, with a curved arm extending therefrom through a slot in the plate, and hung to a pivot on the back of the plate, and nearly in line with its front edge, so that when the door is opened it turns on the said pivot entirely away from the door-post, the pivot being concealed within the post.

It is desirable at times to remove the carriage-door. Formerly this could only be done by removing the screws from the plate on the door-post and taking the hinge bodily from its place. This is not only difficult, but generally very inconvenient.

The object of this invention is the construction of the hinge so that the pivot and its seat—that is, the operative parts of the hinge—may be entirely removed without detaching the plate from the door-post. To this end the invention consists in the construction as hereinafter described, and particularly recited in the claims.

A is the plate of the door-post, and B the plate for the door, both of the usual form. The plate B is provided with an arm, C, curved in the usual manner, and the plate A with a slot, D, through which the arm C works, also, in the usual manner. On the back of the plate A an

arm, E, extends, in the usual manner, for the support of the arm C, and to which the said arm is usually pivoted; but instead of pivoting the arm C to the arm E, I fit the arm C to a shoe, H G. (Shown detached in perspective, 55 Fig. 4.) This shoe has a horizontal flange, G, at the bottom, and a similar flange, H, above, the space between corresponding to and so as to receive the arm C of the plate B. This shoe is also fitted with a lug or stud, L, on its 60 under side. Into the shoe the arm C is hung by a pivot, a, which extends through the arm, as seen in Fig. 3. At the outer or front edge of the plate A a vertical slot is made, opening above and below the slot D sufficient to permit the arm C, with the shoe F thereon, and its stud L, to be passed in, as seen in broken lines, Fig. 3. The arm E is provided with a recess to receive the stud or lug L, and so that when the shoe has been fully inserted, or so 70 as to come flush with the plate A, the lug or stud L will drop into its corresponding cavity in the arm E, which, together with the fit of the shoe in its slot in the plate A, is sufficient to hold the shoe in its place; and when so in 75 place the plate B and the door thereto attached is turned in the usual manner, the arm C working through the slot D.

The vertical slot for the insertion of the arm with its shoe would leave an opening through 80 the plate. To fill this opening I hang therein a closer, P, hinged so as to turn up, as seen in broken lines, Fig. 3, to open the slot, or turned down to fill it, as seen in Figs. 1 and 3; and that it may be held in either its closed 85 or open position, I provide a flat spring, R, on the back of the plate A to bear upon the closer P above its pivot, and also cut a notch, S, in the plate A at the side of the closer, as a convenient means for opening the closer. 90

When it is desired to remove the door or separate the two parts it is only necessary to raise the closer P and lift the arm C, with its shoe, from its engagement with the arm E.

I do not broadly claim a coach-hinge having the part attached to the door detachable from the part attached to the post. 95

I claim—

1. The herein-described concealed hinge, consisting of the plate A, constructed with the 100

arm E on its back, a horizontal slot, D, and vertical slot opening from said horizontal slot, combined with the plate B, with an arm, C, extending therefrom, and pivoted in the shoe H, said shoe H fitted for insertion through the vertical slot in the plate A and engagement with the arm E, substantially as and for the purpose described.

2. The herein-described concealed hinge, consisting of the plate A, constructed with the arm E on its back, a horizontal slot, D, and

vertical slot opening from said horizontal slot, combined with the plate B, with an arm, C, extending therefrom, and pivoted in the shoe H, said shoe H fitted for insertion through the vertical slot in the plate A and engagement with the arm E, and with the closer P for the vertical slot, substantially as described.

FRANK W. TIESING.
